SUCTION CLEANER

Uncas A. Whitaker, Canton, Ohio, assignor to The Hoover Company, North Canton, Ohio, a corporation of Ohio

Application August 14, 1933, Serial No. 685,035

11 Claims. (Cl. 15—6)

The present invention relates to suction cleaners in general and particularly to a new and novel agitator construction for a suction cleaner. More specifically, the invention comprises the provision, in a rotary agitator for a suction cleaner, of a surface-agitating element which is floatingly mounted relative to the rotating agitator body which carries it.

It is an object of the present invention to provide a new and improved rotary agitator for a suction cleaner. Another object is the provision, in a rotary agitator for a suction cleaner, of float-ing surface-contacting agitating elements. Still another object is the provision, in a rotary agitator for a suction cleaner, of counter-balanced floating agitating elements. A still further object is the provision, in a rotary agitator for a suction cleaner, of a freely floating brush element which is counter-balanced. A still further object is the provision, in a rotary agitator for a suction cleaner, of a freely floating rigid positive beating element which is counter-balanced. These and other more specific objects will appear upon reading the following specification and claims and upon considering in connection therewith the attached drawing to which they relate.

In the drawing in which preferred embodiments of the present invention are disclosed:

Figure 1 is a front view of a modern suction cleaner with the agitator constructed in accordance with the present invention embodied therein, a section being shown transversely across the cleaner nozzle;

Figure 2 is a partial cross section through the machine taken at right angles to the showing of Figure 1 and upon the line 2—2 of that figure;

Figure 3 is a section thru the agitator upon the line 3—3 of Figure 1;

Figure 4 is a view in perspective of a floating brush element and its seat removed from the agitator body;

Figure 5 is a section similar to Figure 3 but showing only floating positive beating elements in the agitator;

Figure 6 is a view similar to Figure 4 showing a freely floating beater element positioned within its seat which has been removed from the agitator body;

Figure 7 is a cross section thru an agitator having both brush and beater elements, there being resilient means to bias the elements.

Referring now to Figures 1 and 2 in particular a modern suction cleaner is disclosed in which an unshown motor within the casing 1 drives a suction-creating fan 2 within the fan chamber 3.

Fan 2 creates a reduced pressure within the suc-tion nozzle 4 which is interiorly connected to the fan chamber 3 through the eye 5. The nozzle 4 is provided with front and rear surface-contacting lips 6 and 7, and in the operation of the cleaner the reduced pressure existing within the nozzle 4 results in the lifting of the surface covering undergoing cleaning from the supporting surface into contact with those lips. The motor shaft 8 continues below the fan chamber 3 and 10 into the air passageway connecting the nozzle 4 to the eye 5 and is formed as a driving pulley in order that it may co-operate with the power-transmitting belt 9 which extends forwardly into the nozzle 4 where it drives the rotary agitator 10 15. The cleaner is movably mounted on front and rear supporting wheels 11, 11, and a pivoted handle 12 is provided through which the operator may exert a propelling force in the operation of the cleaner. No invention is claimed to reside 20 in the general arrangement of the cleaner but what is claimed as applicant's invention is the specific construction of the rotary agitator 10 which will hereinafter be more fully described.

Agitator 10 is seen to comprise a cylindrical 25 body 13 which is rotatably mounted upon a through supporting shaft 14 by means of bearings 15, 15. Shaft 14 extends beyond the ends of the body 13 and is removably supported in any suitable manner by the end walls of the nozzle 4. 30 Substantially midway of its length the body 13 is provided with a pulley surface 16 on which seats the power-transmitting belt 9 from the drive shaft 8. In the operation of the machine the agitator rotates about an axis through the sup-35 porting shaft 14 being driven by the belt 9 from the motor shaft.

In the ordinary rotary agitator the surface-agitating means comprise brushes, and in the more advanced type of agitators rigid surface-contacting beater elements are combined with the brush elements to obtain maximum cleaning effectiveness. Heretofore, however, the elements have been fixedly seated upon the agitator body although provisions may have been made to provide for their removal and replacement upon deterioration in the case of the brush elements. In the agitator constructed in accordance with the present invention, however, the brushes and the rigid beater elements are floatingly mounted 45 relative to the body of the agitator and are adapt-ed to give radially upon contacting the surface-covering undergoing cleaning.

Referring again to the drawing the surface-contacting element seat is seen to comprise a 55

member 20 which extends within the normal confines of the agitator body 13. Adjacent each end of each seat 20 an arm 21 is pivotally mounted on the seat, as indicated at 22. Each arm 21 is L-shaped and one end thereof extends to a position exactly at the end of the brush seat while the opposite end thereof extends to a point spaced from the seat. The arms 21, 21 are adapted to support a brush element 23 or a beater element 24 in the seat, the seat ends of the arms 21, 21 being formed with rectangular openings 25, 25 which are adapted to seat and enclose similar rectangular projections 26, 26 upon the ends of the brush or beater elements. As is clearly seen in Figures 4 and 6 one end of the element seat is open and as the arm 21 is of relatively flexible material the brush or beater element may be moved longitudinally in the seat 20 deflecting the arm 21 and permitting the opposite end of the element to be disengaged from its seat 25 thereby permitting the removal of the element from the seat. The insertion of the brush or beater element is exactly the reverse operation.

Upon the opposite side of a radial plane thru the pivot points of the arms 21, 21 from the surface-contacting element carried thereby is a mass or counter-balance 27 whose function it is, in the operation of the agitator, to counter-balance the centrifugal force of the brush or beater element. In order to provide a freely floating element the mass of weight 27 is such that its moment about the pivotal axis of arms 21, 21 in the operation of the agitator is equal to the moment of the brush or beater element 23 or 24 about the same axis. Were the weight 27 not provided for each element the centrifugal force of that element would be such, at high speed rotation, that the construction would be substantially the equivalent of a rigid mounting.

40 Referring now to Figure 7 a slightly modified construction is shown in which leaf springs 30, 30 are provided within the agitator body 13, being mounted thereon and extended into contact with the counter-balancing weights 21, 21 for the purpose of eliminating play and undue pivoting of the surface-contacting elements. The spring 30 can be made to exert such force that the surface-contacting element is normally held at any desired position relative to the surface of the agitator body, or may be so positioned that it is only effective upon the surface-contacting element being contacted by the surface covering and deflected inwardly.

I claim:

55 1. In a suction cleaner, a rotary agitator including a surface-contacting agitating element, means pivotally mounting said element about an axis circumferentially displaced from itself and substantially parallel to the axis of rotation, and means opposing the pivotal movement of said element about its axis under centrifugal force comprising a counterbalance connected to said element and pivoted upon the opposite side of said axis.

65 2. In a suction cleaner, a rotary agitator including a surface-contacting agitating element comprising a rigid back carrying flexible bristles mounted for movement in the direction of and away from the axis of rotation and a counterbalance subjected to centrifugal force and connected to said brush to oppose the centrifugal force thereof.

70 3. In a suction cleaner, a rotary agitator including a rigid surface-contacting agitating ele-

ment movable between minimum and maximum radial extensions and a movable counterbalance subjected to centrifugal force and connected to said element to oppose the centrifugal force

5 4. In a rotary agitator for a suction cleaner, a cylindrical body, means supporting said body for rotation about its longitudinal axis, a surface-contacting element extending from within said body and projecting to a point beyond the surface thereof, means mounting said element for free inward and outward movement, and a counterbalance movable relative to said body opposing outward movement of said element under the action of centrifugal force in the rotation of said body without opposing inward radial movement.

10 5. In a suction cleaner, a rotary agitator including a cylindrical body, means supporting said body for rotation about its longitudinal axis, surface-contacting brush and rigid beater elements extending from within said body and projecting to positions beyond the surface thereof, means mounting said brush and beater elements for free inward and outward movement, and counterbalances opposing outward movement of said brush and beater elements under the action of centrifugal force in the rotation of said body without opposing inward radial movement.

15 25 6. In a rotary agitator for a suction cleaner, a surface-contacting element, means pivotally mounting said element about an axis circumferentially spaced from itself, and a mass pivotally mounted upon the opposite side of the pivotal axis and connected to said element, the moments of the element and the mass about the said pivot point being substantially equal in the rotation of the agitator in order to obtain a freely floating relationship.

30 40 7. In the construction defined by claim 6 a spring to oppose the radial thrust of said beater element upon said element contacting the surface covering undergoing cleaning.

35 45 8. In a rotary agitator for a suction cleaner, a surface-contacting agitating element mounted for inward and outward displacement, and means counteracting the effect of the centrifugal force of said element at any speed of rotation of the agitator to maintain the force required to displace said element substantially constant, said means comprising a counterbalance subjected to centrifugal force in the rotation of said agitator and connected to said element to oppose its outward movement under the action of centrifugal force.

50 55 9. The construction recited in claim 8 characterized in that means are provided to dampen the movements of said element.

60 65 10. In a rotary agitator for a suction cleaner, a surface-contacting agitating element movable between positions of minimum and maximum radial extensions, resilient means arranged to oppose the movement of said element to its position of minimum radial extension, and means counteracting the effect of the centrifugal force of said element at any speed of rotation of the agitator to maintain the force required to displace said element substantially constant.

70 75 11. The construction recited by claim 10 characterized in that said neutralizing means comprises a counterbalance subjected to centrifugal force in the rotation of said agitator and connected to said element.

UNCAS A. WHITAKER.
